UNITED STATES PATENT OFFICE.

GEORGE A. LE FEVRE, OF ORANGEBURG, NEW YORK.

APPARATUS FOR MAKING FENCE-POSTS.

No. 833,882.

Specification of Letters Patent.

Patented Oct. 23, 1906.

Application filed August 21, 1905. Serial No. 274,997.

To all whom it may concern:

Be it known that I, GEORGE A. LE FEVRE, of Orangeburg, in the county of Rockland and State of New York, have invented a new and Improved Apparatus for Making Fence-Posts, of which the following is a full, clear, and exact description.

My invention relates to improvements in an apparatus for making fence-posts such as 10 have their body portion formed of concrete or other cement; and the object of my invention is to produce a simple apparatus which can be conveniently operated by a single person and which is adapted to give to a plastic 15 post the desired shape and is also constructed so that a binding-core can be easily applied to the body portion of the post to prevent the post from breaking. My invention is especially intended to provide a simple 20 form of apparatus which can be used by a farmer, for instance, to make his own fence-posts and which is constructed so that a particularly strong post can be produced and also which is intended to produce a post 25 which will not heave or be displaced owing to climatic changes.

With these ends in view my invention consists of certain features of construction and combinations of parts, which will be herein- 30 after described and claimed.

Reference is to be had to the accompanying drawings, forming a part of this specification, in which similar figures of reference indicate corresponding parts in all the views.

35 Figure 1 is a longitudinal section of the apparatus embodying my invention, showing the cement or plastic material in the mold. Fig. 2 is a detail elevation of a preferred form of core which is used in connection with the 40 mold and forms a part of the apparatus. Fig. 3 is a cross-section on the line 3 3 of Fig. 1. Fig. 4 is an elevation of a post formed in the mold shown in Fig. 1. Fig. 5 is a broken detail sectional elevation showing a slight 45 modification of the device which is intended to produce holes through the post, and Fig. 6 is a broken elevation of a post made by the apparatus shown in Fig. 5.

My apparatus comprises a mold which can 50 be given the shape of the desired fence-post, and for convenience I make the mold in two parts 10, which can be fastened together in any convenient way or hinged, if desired; but

I have shown them connected by ordinary swing-bolts 10^a on one member which engage 55 lugs 10^b on the opposite member. This form of fastening is a common one and is referred to simply to make the case clear. The mold is widened at the top, as shown at 11, in order that the post, which is shaped in it, can 60 be widened at this part, which forms the bottom portion of the post, as shown at 11^a in Fig. 4. It has been found in practice that where a post is considerably enlarged at the bottom it is not readily displaced by frost, 65 moisture, &c.

The bottom of the mold corresponds to the top portion of the post formed therein, and while the mold would give the desired shape to the post without any foot part I prefer to 70 use a foot 12, which is secured to the bottom portion of the mold and has, preferably, strengthening-ribs 13. The form of the support is not essential; but the object of it is to enable one person to conveniently form posts. 75 With the construction shown a person can stand the mold on its foot 12, then insert the core, as presently described, and then fill the mold, whereas if the foot were not used it 80 would need a person to support the mold or some extraneous devices to support it.

In connection with the mold and forming a part of the post-making apparatus I use a core 14, which has a plurality of wings 15 and 85 16, and four of such wings are sufficient for most purposes. A convenient way to form the core is to have a cross-piece 15 with slots therein and have two wings 16, which are arranged at right angles to the cross-piece or web 15 and which have lugs 17 adapted to enter the slots and be turned over, as shown in Figs. 1, 2, and 3. This particular construction of core is not essential, however, and if the form of core shown is used it can be struck up in any convenient way. The core 95 is intended to fit nicely in the mold, and the wings of the core are provided with holes 18, so that when the plastic material is placed in the mold it will pass through the holes 18, forming keys, as in Fig. 1, which securely 100 lock all parts of the post together, and the core gives to the post a strength which will enable it to withstand all ordinary shocks. If desired, pins or pipes 19, as in Fig. 5, can be inserted through holes which may be left 105 in the mold 10 and through corresponding

holes in the wings 15 or 16 of the core, and then when the post is formed holes 19^a will be produced in the post, (see Fig. 6,) which holes are adapted to receive pipes in case a 5 pipe-fence is formed, or wires can be thrust through them, if necessary.

In Fig. 5 I show two lugs 15^a on the wings 15, and these little lugs serve to hold the core 14 from actual contact with the mold 10, and 10 so the wing portions of the core are completely covered by cement except at the points where the small lugs project, and thus the life of the core, and consequently of the post, is prolonged.

15 In using the apparatus the mold is stood on end, as in Fig. 1, the core 14 is placed in the mold, and the plastic material which is to form the post is then poured in and, if necessary, tamped in. After the material is 20 set the mold can be opened and the post is ready for use. It will be seen that a person with two or three molds and a sufficient quantity of cores could make posts very rapidly and would be able to produce a cheap 25 and substantial post. It will be observed also that the apparatus which I have shown is constructed so that the core fits nicely in the mold, and therefore the mere act of dropping it in makes the device ready for use.

Having thus fully described my invention, 30 I claim as new and desire to secure by Letters Patent—

1. An apparatus of the kind described, comprising a mold of two longitudinally-separable parts, said parts being abruptly enlarged at one end which is open and provided with fixed flanges at the opposite end, said flanges forming a foot on which the mold can stand. 35

2. An apparatus of the kind described, 40 comprising a mold open at one end and tapering toward the other, the said mold being abruptly enlarged near its open and larger end and provided at its opposite end with a supporting-foot. 45

3. An apparatus of the kind described, comprising a mold having two longitudinally-separable parts abruptly enlarged near one end which is open, integral flanges at the opposite end and outer sides of the mold, said 50 flanges forming a supporting-foot, and means for fastening the two parts of the mold together.

GEORGE A. LE FEVRE.
